CLAIM

The ornamental design for a car handle, as shown and described.

DESCRIPTION

FIG. 1 is a top, right, front perspective view of a car handle showing our design therefor;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.
